MICROWAVE TUBE

Martin Ruderfer, Brooklyn, N. Y.

Application October 21, 1949, Serial No. 122,614

3 Claims. (Cl. 315—5)

1

The present invention relates to improvements in evacuated electron tubes suitable for operation in the ultra high frequency range, where the wave length is of the order of centimeters or less.

An object of this invention is to provide an electron tube of the character mentioned, of novel, improved and simplified construction, which may be used as an oscillator or an amplifier of microwave energy.

Heretofore, electron tubes operating in the centimeter range, have been of two general types, namely, those of low power and continuous output which have proven inefficient, and those of high power and intermittent or pulsed output, which have proven to be reasonably efficient. The high power microwave apparatus operating at high voltages as the "Magnetron," require the use of comparatively large magnets and specially designed pulsing means, all of which auxiliary equipment is expensive and space consuming.

It is therefore another object of this invention to provide a microwave tube which combines the advantages of previous types without the disadvantages, of novel, simple and cheap construction, capable of high power at good efficiency in continuous or intermittent duty; said devices being controlled directly by low voltage circuits, and easily pulsed by using simple and readily available means having standard components, thus eliminating all expensive and large auxiliary apparatus heretofore required for high power tubes.

Another object of this invention is to provide a novel and improved electron discharge device of the class set forth, which permits a variation of frequency of oscillation over a wide range.

A further object hereof, is to provide a high power microwave oscillator which does not depend upon secondary emission from a cathode surface for its operation; thus affording longer life to the device.

Other objects and advantages will become apparent as this disclosure proceeds.

In the accompanying drawings forming part of this specification, similar characters of reference indicate corresponding parts in all the views.

Fig. 1 shows an embodiment of my present invention, consisting essentially of an electron source and a cavity resonator. The embodiment illustrated is based upon standard tube construction. The circuit diagram included in this view, indicates the device used as an oscillator.

2

Fig. 2 is a perspective view, partly in section, of the cavity resonator included in the embodiment illustrated in Fig. 1.

Fig. 3 shows a modified embodiment of this invention based upon standard construction.

Fig. 4 is an enlarged sectional view taken at lines 4—4 in Fig. 3. The circuit diagram included herein, indicates the device used as an amplifier.

10 Fig. 5 shows another modified form of resonator discussed herein.

In the drawings, the numeral 15 designates generally a cavity resonator positioned within the vacuum interior of an envelope 16. This 15 envelope, made of glass or other insulative material, also houses an electron source means, which may be the conventional electron gun, diagrammatically shown and indicated generally by the numeral 17, comprising a heating filament 18, a cathode 19 and a control grid 20.

The cavity resonator is a hollow body having a pair of opposite spaced central wall portions. One of these wall portions is perforated, to serve as the screen grid 21, which may also be a grid 25 of wires or other suitable structure known in the art. The second wall portion serves as a plate 22. The remainder of the body of the resonator may be of thin metal sheeting to form the hollows, or what herein shall be referred to as the cavities 23 and 24. If desired, top and bottom walls 25 and 26, which may be of insulative material, may be added to form the structure into a hollow casing, which form is found most practical and efficient. A loop 27 may be positioned, inserted in one or both of said cavities, through a bushing 28 of insulative material, the inside end of the loop being in electrical contact with the cavity wall. A common lead for the screen 21 and the plate 22, may be connected along the center of said plate as shown at 29. The cavity resonator 15, is so positioned in the envelope 16, that the screen 21 is between the electron gun 17 and the plate 22.

It may sometimes be desirable to connect the 45 screen grid 21 and plate 22 directly, thus eliminating the side cavities and affording the minimum cavity volume, by side walls. The resulting cavity is therefore rectangular in section, two opposite sides of the rectangle being the screen 21 and plate 22.

The cavity resonator and its manner of association with the electron gun, may take on many shapes and forms. In the embodiment illustrated in Figs. 3 and 4, the cavity resonator 15' is a hollow body having the incidents of structure as

aforementioned to form the grid 21' and the plate 22', and whose cavity 23', is a perimetral race, and hence a continuous cavity completely surrounding said grid and plate. The perimetral cavity may be other than circular, and the cross sectional shapes of the various cavities illustrated may be other than circular.

The glass envelope 16' housing the electron gun 17', may also house the cavity resonator 15', or else as shown, the envelope may be a shell having said resonator mounted thereon so that the screen grid 21' is across its mouth. The loop 27' is positioned, inserted into cavity 23', through the insulative bushing 28'; the inside end of the loop being in electrical contact with the cavity wall. A common lead for the grid 21' and plate 22', may be at the center of the plate as at 29'. When the screen grid 21' is mounted across the mouth of the envelope, it is preferable to locate the common lead at the junction of screen grid 21' and envelope 16', in which case the envelope may be of conductive material and may serve as the aforementioned common lead.

Operation of the devices described, depends upon the secondary emission of electrons from the surface of the plate facing the grid. To facilitate this, it is desirable to coat such surface of the plate and even the surface of the screen grid facing the plate with one or more materials which aid the production of secondary electrons, as caesium oxide, barium oxide and other suitable materials known in the art.

Referring to the tube device shown in Fig. 1, when the electron gun 17 is operated, a stream of electrons emanating from the cathode 19, is initially accelerated towards the plate 22, by the positive potential applied to plate 22 and grid 21, by means of the battery 30. Some of these primary electrons are captured by the grid 21, but others travel through said grid and strike the plate 22. This causes the emission from said plate, of a number of secondary electrons, some of which are attracted to said plate 22 and some to the grid 21. For each primary electron, there are produced a large number of secondary electrons, so that the secondary electron flow from plate to screen and around the periphery of the conductors determining the cavities 23 and 24, to the battery 30, is greater than the primary electron flow from grid 21 to plate 22. Such secondary electron flow to the grid 21, momentarily causes the potential of said grid to decrease, and the potential of the plate 22 to increase, so that less secondary electrons are attracted to the grid 21, and more to the plate 22, thereby causing the secondary electron flow to decrease. This in turn produces a transient increase in potential of the grid 21, and a corresponding decrease of potential of the plate 22, so that the secondary electron flow again increases. Thus a fluctuating current is created along the sides of the cavities 23 and 24; the frequency of oscillation being determined primarily by the resonant frequency of the cavities 23 and 24, and to a lesser degree by the spacing between the plate 22 and the grid 21, as well as by the velocity of the primary electrons from the gun 17.

The current circulating along the sides of the cavities 23 and 24, produces an oscillating magnetic field in said cavities. Hence the loop 27 is used to tap this oscillating energy for useful purposes, as for instance to an antenna 31, in which instance the device functions as an oscillator. Used in this manner as an oscillator, if the control grid is connected directly to the cathode, 75

continuous oscillations will result. For producing pulses of oscillation, the circuit shown in Fig. 1 may be used. The grid is connected to one side of the secondary of a transformer 34, and the other side of the secondary is connected to the negative terminal of battery 33. The positive terminal of battery 33 is connected to the cathode 19. The potential of battery 33 is such that the negative voltage on the control grid 20 normally prevents any flow of primary current from cathode to screen grid 21. The primary of transformer 34 is connected in series with a battery 35 and a switch 36. Operation of the switch 36 causes a momentary positive pulse to be induced in the secondary of transformer 34 of sufficient magnitude that a flow of current for the duration of the pulse results from cathode to screen grid 21, thereby producing a pulse of oscillations.

The tube device of Fig. 4 of course operates in like manner when in the circuit shown in Fig. 1.

The frequency of oscillation, of which the resonant frequency of the cavity is a factor, may be slightly varied by change of battery potential 30, or the voltage applied on the control grid 20 of the electron gun. When the exterior surface of the plate 22' is exposed as in Fig. 4, it is also possible to vary the frequency by moving the plate 22' to change its distance from the grid 21', by suitable mechanical means as for instance an adjustment screw 40 engaged in a frame piece 41 which is fixed in relation to the device 16'. Any other suitable way to change the cavity shape, will accomplish the same result. In the embodiment shown, the conductor defining the cavity 23', in electrical connection with the plate 22' and the grid 21', being of thin metal, will be sufficiently springy to urge return of said plate to normal unmoved position.

Referring to Fig. 4, one or more grids may be placed between the plate and screen grid. Such additional grid shown at 32, is connected for instance to a low amplitude ultra-high frequency source, as for instance an input signal at 37. This grid 32 will control the flow of secondary electrons from plate 22' to the grid 21', and cause the output tapped by 27', to vary in accordance with the low amplitude source 37. Thus the device will act as an amplifier. The tube device of Fig. 1, if provided with a grid akin to 32, between plate 22 and grid 21, would of course operate in like manner when in the circuit shown in Fig. 4.

The present invention is capable of numerous forms and various applications without departing from the essential features herein disclosed. It is therefore intended and desired that the embodiments shown herein shall be deemed illustrative and not restrictive and that the patent shall cover all patentable novelty herein set forth; reference being had to the following claims rather than to the specific description herein to indicate the scope of this invention.

I claim:

1. An envelope, means within said envelope to emit a stream of charged particles in a path in a given direction within the envelope, a plate positioned across the path of said stream, having the characteristic that it emits secondary electrons from its surface facing said means; such surface of the plate being of a material which aids such emission, a grid positioned across said path between said means and the plate and spaced from said plate, electrically continuous walls at least in part electrically conductive, electrically connecting the plate and grid and forming therewith an unobstructed cavity resonator in extension of, communicative with and including the space be-

tween said grid and plate and means carried by the envelope to conduct electromagnetic energy occurring within said cavity resonator, to a point exterior the cavity resonator.

2. An envelope, means within said envelope to emit a stream of charged particles in a path in a given direction within the envelope, a plate positioned across the path of said stream, having the characteristic that it emits secondary electrons from its surface facing said means; such surface of the plate being of a material which aids such emission, a grid positioned across said path between said means and the plate and spaced from said plate; the surface of the grid being of a secondary emissive material which aids emission from the grid, walls at least in part electrically conductive, electrically connecting the plate and grid and forming therewith an unobstructed cavity resonator in extension of, communicative with and including the space between 20 said grid and plate and means carried by the envelope to conduct electro-magnetic energy occurring within said cavity resonator to a point exterior the cavity resonator.

3. A device as defined in claim 1, wherein the cavity resonator is part of the envelope, the grid partitions the envelope and the entire envelope is of electrically conductive material whereby any part thereof may serve as the lead to grid and plate.
